UNITED STATES PATENT OFFICE

99,549

DESIGN FOR A DECORATIVE WATERPROOF COVERING FOR CLEANSER CANS AND SOAP FLAKE BOXES

Bernard G. Klein, Chicago, Ill.

Application September 3, 1935, Serial No. 58,416

Term of patent 7 years

To all whom it may concern:

Be it known that I, Bernard G. Klein, a citizen of the United States, residing at Chicago, in the county of Cook and State of Illinois, have invented a new, original, and ornamental Design for a Decorative Waterproof Covering for Cleanser Cans and Soap Flake Boxes, of which the following is a specification, reference being had to the accompanying drawing, forming part thereof.

In the drawing, the figure is a perspective view of a decorative covering embodying my new design.

The distinctive features of my design include

shirred ruffles at the top and bottom edges respectively of the body portion, the line of attachment of each ruffle to the body portion being relatively much closer to one edge of the ruffle than the other, and each ruffle at its said line of attachment being finely shirred in contrast to the coarser stirring of the ruffle itself.

I claim:

The ornamental design for a decorative waterproof covering for cleanser cans and soap flake boxes substantially as shown and described.

BERNARD G. KLEIN.
